FLEXIBLE BRACELET OF THE ARTICULATE TYPE

Karl C. Augenstein, Cranston, R. I., assignor to Speidel Corporation, Providence, R. I., a corporation of Rhode Island

Application September 15, 1950, Serial No. 184,994

8 Claims. (Cl. 224—4)

1

Bracelets or bands of the above type are subject to the objection that their articulate joints provide numerous reentrant portions or openings which are dirt collecting and virtually impossible to keep clean. Hence the appearance of this type of bracelet although originally attractive, is soon impaired. Moreover the manufacture of such bracelets with accurately interfitting parts involves time-consuming operations which appreciably increase the cost of manufacture.

The principal object of the present invention is to provide a bracelet or band of the above type which is not only of pleasant and attractive appearance, but also overcomes the aforementioned objections.

A more specific object is to provide a simple and efficient means for retracting the pivotal units of the bracelet so that they will snugly embrace or fit about the wrist of the wearer and thus presents a more attractive appearance.

Further objects will be apparent from consideration of the following description and accompanying drawings, wherein:

Fig. 1 is a top plan view of my new bracelet or band with the sections in outstretched position;

Fig. 2 is a side elevation of the bracelet as it appears when being worn or displayed;

Fig. 3 is a longitudinal horizontal section through one of the articulate sections;

Fig. 4 is a longitudinal vertical section through the articulate sections shown in Fig. 3;

Fig. 5 is a fragmentary section similar to Fig. 3 but showing a retractor of modified construction;

Fig. 6 is an enlarged longitudinal vertical section through one of the end connectors and associated unit or link;

Fig. 7 is a bottom view of the parts shown in Fig. 6;

Fig. 8 is a transverse vertical section adjacent to the free end portion of the connector link;

Fig. 9 is a view similar to Fig. 8, but illustrating the manner in which the coupling pin is released;

Figs. 10 and 11 are enlarged side elevations of the retractor mechanism when in retracted and extended positions, respectively;

Fig. 12 is a detail showing the manner in which the retractor chain is secured to the shaft;

Fig. 13 is an enlarged top plan view, with parts broken away, of the retractor mechanism;

Fig. 14 is an exploded view of the constituent parts of the casing of the retractor mechanism;

Fig. 15 is an enlarged isometric of one of the articulated units or links; and

Fig. 16 is an exploded view of a pair of interconnected elements constituting the bottom walls of a pair of links.

The embodiment herein shown for the purpose of illustration comprises two articulate sections 1 and 2 each having an end connector 3 for attaching the section to a wrist watch or ornamentation 4, and a terminal link 5 through which extends a retractor strand or chain 6 for yieldingly urging

2

the two sections toward each other so that they will tend to embrace the wrist of the wearer more snugly. Each of the sections 1 and 2 comprises a series of interconnected links or units 10 (Figs. 4, 6 and 15) of geometrically similar shape and of progressively decreasing size from the end connector 3 to the terminal link 5.

Each of the units 10 comprises a generally semi-cylindrical shell or tubular element having adjacent to its opposite end portions diametrically disposed apertures 11 and 12 (Fig. 15). The outer ends of the units are each formed with an integral extention 14 having an upwardly extending arcuate lip 15, and the inner ends of the units are each formed with an inwardly directed arcuate lip 16 defining a mouth for receiving the extention 14 and lip 15 of the adjacent unit when the links are assembled so that the apertures 12 of one unit are aligned by the apertures 11 of the adjacent unit, as shown more clearly in Figs. 4 and 6.

The bottom walls of the units 10 comprise dished elements 18 (Figs. 4, 7 and 16) which snugly fit between the longitudinal edges of the units and the elements are formed with integral parts rolled to provide a central sleeve 20 at one end and a pair of spaced sleeves 21 at the other end, the construction and arrangement of parts being such that when the elements 18 are assembled within the shells or units 10, the sleeve 20 of each unit is aligned with the apertures 12 and the sleeve 21 is aligned with the apertures 11; and when the units are assembled, the sleeves 20 of one unit fit in the openings between the sleeves 21 of the adjacent unit so that a pintle 22 may be passed through the apertures and sleeves so as pivotally to interconnect the units, as shown in Figs. 4, 6 and 7.

The surface contour of the units 10 and the shape of the depending lips 16 are such that the latter is at all times in contiguous relation to the former, regardless of the angular position of the units relative to each other, as indicated in Fig. 2, thus eliminating dirt-collecting openings, recesses, etc., and presenting a more attractive appearance. The inner end of each terminal link 5 is formed similar to the inner end of each unit 10, being provided with an integral extention 14 having an outstanding lip 15 (Fig. 4), but its outer end converges somewhat to form a small opening through which the retractor chain 6 passes. Similarly the bottom wall of each terminal link 5 is formed at its inner end with spaced sleeves 21 to interfit with sleeve 20 of the adjacent unit 10, but the outer end of the bottom wall is rolled, as indicated at 23 in Fig. 4, to provide a smooth continuous surface. In order to insure a smooth operation of the chain or strand 6 in moving back and forth within the sections, I provide a chain slide 24 which consists of a tapered strip of stainless steel or other suitable material (Figs. 3, 4 and 6) extending from the innermost sleeve 21 to the rolled edge 23, the inner end being

formed with a sleeve 25 (Figs. 6 and 7) which fits about the pintle 22 between the sleeves 21, thus anchoring the slide in position.

Each of the connector links 3 comprises a shell or housing 30 having a surface configuration simulating that of two interconnected units, thus preserving the characterizing motif of the section. Each connector link has a bifurcated or spaced inner end 31 to receive the coupling loop of a wrist watch or ornamentation 4, and an outer end conforming generally with that of a unit 10, being formed with a depending lip 16 embracing the curved surface of the inner unit 10, as shown more clearly in Fig. 6. The bottom wall 32, of each connector snugly fits between the longitudinal edges of the shell 30 and is held in position by inwardly bent tabs 35 (Fig. 7) integral with the shell 30. The outer end of the bottom wall terminates in contiguous relation to the sleeves 21 and 25 and the opposite end of the bottom wall is formed with an extension 33 (Figs. 6-9) which curves inwardly to merge with the bifurcated end 31 of the sleeve.

With the construction and arrangement of parts above described the connector 3, terminal link 5 and intervening units 10 of each section may be swung from a "stretched out" position, as shown in Fig. 1, to a "curled up" position, such as illustrated in Fig. 2, the swinging movement of each unit relative to the adjacent unit, being limited by the engagement of the outwardly extending lip 15 with the depending lip 16 which not only provides a stop, but also a closure element contiguous to and giving the appearance of merging with the surface of the adjacent unit regardless of their angular position.

Although the coupling element of the connector links 3 may be of any conventional form, the type herein shown is particularly advantageous as it permits a quick, convenient attachment and detachment of the watch and band. Referring to Figs. 6 to 9, the walls of the bifurcated end 31 are formed with aligned apertures 40 to receive a coupling pin 42, the aperture 40a (Fig. 8) on one of the outer walls being smaller than the other aperture so as to prevent the coupling pin 42 from being pushed therethrough. The end portion of the coupling pin 42 adjacent to the smaller apertures 40a is formed with a circumferential groove defining a locking shoulder 44 and a conical-like surface or cam element 45, as shown in Figs. 8 and 9.

Secured to the bottom wall extension 33 by a rivet 46 is latch spring 48, one end of which is formed by a cam-like nose 47 and its outer end with a hooked locking finger 49. The design of the parts is such that when the coupling pin is in operative position, the cam-like nose 47 of the latch spring 48 engages the shoulder 44 and cam surface 45 and the finger 49 at the opposite end of the spring 48 is flexed outwardly by the plain end of the coupling pin 42, as shown in Fig. 8. Hence, the coupling pin 42 may be slid from operative or locking position (Fig. 8), wherein it passes through the usual opening in the coupling member of a wrist watch or ornamentation, to the left by inserting a pin or the like pointed instrument through the apertures 40a, thereby forcing the grooved end to disengage the cam nose 47. Such axial movement is limited by the engagement of the locking finger 49 with the shoulder 44, as shown in Fig. 9, which prevents complete removal of the pin 42. When in released or unlocking position (Fig. 9) the coupling member of the wrist watch or ornamentation may be moved

to and from a position between the bifurcated ends of the connector link, and coupling the parts is merely a matter of moving the pin 42 to the right (Fig. 9) until the grooved end engages the 5 marginal portions about the aperture 40a, in which position the cam nose 47 snaps into locking position.

Although the connector 3, terminal link 4 and intervening units 10 may be pivotally connected so that friction or other means holds them in one position or another, the retractor strand 6 is preferably employed yieldingly to urge the terminal links together. The retractor strand 6 may consist of any suitable flexible material such as a cord, chain or the like, one or both ends of which are connected to a retractor mechanism (Figs. 4, 10-14) or 50a (Fig. 5) operative to draw the strand or chain 6 inwardly, thus swinging the links or units 10 to curled position so that they embrace the wrist of the wearer with comfortable snugness.

Referring to Figs. 10 to 14, the retractor 50 comprises a housing consisting of the interfitting plates 51, 52 and 53 which provide the outer and intermediate walls defining two chambers 54 and 55 (Fig. 11). The outer walls 51 and 53 are formed with integral lateral tabs by means of which the parts are held in position and all three plates are formed with openings 56 which are aligned in the assemblage to receive a suitable shaft 58. Secured to one part of the shaft 58 is one end of the strand or chain 6, the other end of which may be similarly secured to a retractor 50 or otherwise anchored in the other section of the bracelet. The inner end of a spiral watch spring 60 is anchored to another part of the shaft 58 and the other end of the spring is secured to one of the lateral flanges or tabs of the plate 51, the arrangement being such that the chain 6 is wound up about the shaft within the chamber 55 and the spring 60 winds and unwinds about the shaft within the chamber 54. The entire assemblage 50 has a tight fit within the shell 30, as shown in Figs. 3, 4 and 6, with retracted chain 6 passing through the units of one section to and through those of the other section.

Other forms of retractors may be employed and as illustrative of another type is that shown in Fig. 5, which comprises a supporting plate 70 fitting within the shell 30 and carrying a suitable shaft 71 which supports a pulley or grooved wheel 72. One end of a helical tension spring 74 is secured to a hook 100 carried by one of the bottom walls, and this spring extends over the pulley 72 with its other end attached to the inner end of the retractor chain 6a, as indicated at 75. Outward movement of the retractor chain 6a not only stretches the spring 74, but also carries it over the pulley 72 so that a greater movement of the chain for a given pull on the spring is attained than would otherwise be possible.

It will be noted that with the construction and arrangement of parts herein shown and described the bracelet or band consisting of the end connectors 3, terminal links 5, intervening links 10 and retracted chain 6 may readily be connected with a wrist watch or the like ornamentation and the entire assemblage slipped or applied about the wrist of the wearer without making the usual adjustments characteristic of extensible linkages and where the retractor chain 6 is employed it holds the units of each section snugly against the wrist of the wearer.

While I have shown and described one desirable embodiment of the invention, it is to be

understood that this disclosure is for the purpose of illustration and that various changes and modifications may be made without departing from the spirit and scope of the invention as set forth in the appended claims.

I claim:

1. A watch band comprising two flexible, non-extensible sections each adapted to be bent into a generally semicircular shape so as to embrace less than half of the circumference of the wrist of the wearer with adjacent ends in spaced relation, each section having at one end a connector for attaching the section to a wrist watch or the like, each section comprising a plurality of hollow units pivotally connected in end-to-end relation, a strand member having its opposite ends secured within said sections and an intermediate portion extending through the free ends of said sections, and a spring within at least one of said sections and acting on the adjacent end portion of said strand member for drawing it into the section, thereby to urge said free ends together.

2. A watch band comprising two flexible, non-extensible sections each adapted to be bent into a generally semicircular shape so as to embrace less than half of the circumference of the wrist of the wearer with adjacent ends in spaced relation, each section having at one end a connector for attaching the section to a wrist watch or the like, each section comprising a plurality of hollow units pivotally connected in end-to-end relation, a strand member having its opposite ends secured within said sections and an intermediate portion extending through the free ends of said sections, and retracting means within at least one of said sections of one of said sections acting on the adjacent end portion of said strand member to draw it into the section, thereby to urge said free ends together.

3. A watch band comprising two flexible, non-extensible sections each adapted to be bent into a generally semicircular shape so as to embrace less than half of the circumference of the wrist of the wearer with adjacent ends in spaced relation, each section having at one end a connector for attaching the section to a wrist watch or the like, each section comprising a plurality of hollow units pivotally connected in end-to-end relation, a strand member having its opposite ends secured within said sections and an intermediate portion extending through the free ends of said sections, and retracting means comprising a coiled spring within a unit of at least one of said sections, said coiled spring being associated with the adjacent end of said strand member to draw it into the section, thereby to urge said free ends together.

4. A watch band comprising two flexible, non-extensible sections each adapted to be bent into a generally semicircular shape so as to embrace less than half of the circumference of the wrist of the wearer with adjacent ends in spaced relation, each section having at one end a connector for attaching the section to a wrist watch or the like, each section comprising a plurality of hollow units pivotally connected in end-to-end relation, a strand member having its opposite ends secured within said sections and an intermediate portion extending through the free ends of said sections, and retracting means comprising a helical tension spring within a unit of at least one of said sections remote from the free end thereof and connected to the adjacent end of said strand member so as to draw it into the section, thereby to urge said free ends together.

5. A watch band comprising two flexible non-extensible sections, each having at one end a connector for attaching the section to a wrist watch, or the like, each section comprising a plurality of hollow units pivotally connected in end-to-end relation, a strand member having its opposite ends secured within said sections and an intermediate portion extending through the free ends of said sections, and retracting means within at least one of said sections for drawing said strand member into the section, thereby to urge said free ends together, said retracting means comprising a freely rotatable shaft, a helical spring around one part of the shaft, one end of said spring being secured to the shaft and the other end being anchored and said strand being attached to another part of the shaft adjacent the helical spring whereby the tension of the helical spring urges the shaft to rotate and wind the strand around the shaft.

6. A watch band comprising two flexible non-extensible sections, each having at one end a connector for attaching the section to a wrist watch, or the like, each section comprising a plurality of hollow units pivotally connected in end-to-end relation by pivotal connections which extend transversely of the hollow units, a strand member having its opposite ends secured within said sections and an intermediate portion extending through the free ends of said sections, a resilient strip secured within each section and overlying the pivotal connections between the links, the portions of said strand member within the sections passing over said pivotal connections and over said flexible strip, and retracting means nested within at least one of said units of one of said sections and acting on the adjacent end portion of said strand member to draw it into the section, thereby to urge said free ends together.

7. A device in accordance with claim 1 also comprising a pulley mounted in one of said hollow units, said spring extending over said pulley.

8. A watch band comprising two flexible, non-extensible sections, each having at one end a connector for attaching the section to a wrist watch, or the like, each section comprising a plurality of hollow units pivotally connected in end-to-end relation by pivotal connections which extend transversely of the hollow units, a strand member having its opposite ends located within said sections and an intermediate portion extending through the free ends of said sections, the portions of the strand member within the sections passing over the pivotal connections between the links, and a spring within at least one of said sections and acting on the adjacent end portion of said strand member for drawing it into the section and thereby to urge said free ends of said sections together.
